(57) CLAIM

The ornamental design for a shoe upper, as shown and described.

DESCRIPTION

FIG. 1 is a perspective view of a shoe upper showing our new design;

FIG. 2 is a side view thereof;

FIG. 3 is a side view thereof, opposite that is shown in FIG. 2;

FIG. 4 is a front view thereof;

FIG. 5 is a rear view thereof; and,

FIG. 6 is a top plan view thereof.

Please note that the Figures include broken, dash-dot-dash and solid lines. The area within the solid and dash-dot-dash lines forms the claimed design. The area within the broken lines is environmental. Color, contrast and texture form no part of the claimed design in any of the Figures.
